United States Patent Office

Des. 212,258

Patented Sept. 17, 1968

212,258

BEVERAGE VENDING MACHINE, OR SIMILAR ARTICLE

Richard T. Cornelius, Minneapolis, and Clark L. Lofgren,
Golden Valley, Minn., assignors to The Cornelius Com-
pany, Anoka, Minn., a corporation of Minnesota

Filed Nov. 9, 1967, Ser. No. 9,342

Term of patent 14 years

(Cl. D52—3)

FIG. 1 is a perspective view showing the front and one side of a beverage vending machine showing our new design, the other side having substantially the same appearance.

FIG. 2 is an enlarged front elevational view thereof.

FIG. 3 is a top view thereof in reduced scale.

The back is plain and unornamented.

We claim:

The ornamental design for a beverage vending machine, or similar article, substantially as shown and described.
